(57) **CLAIM**

The ornamental design of a gusset and seat panel for a pant garment, as shown and described.

DESCRIPTION

FIG. 1 is a perspective view of a first embodiment of a gusset and seat panel according to my design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and

FIG. 8 is an environmental perspective view showing the gusset and seat panel of FIG. 1 sewn into a pant garment;

FIG. 9 is a perspective view of a second embodiment of a gusset and seat panel according to my design;

FIG. 10 is a top view thereof;

FIG. 11 is a bottom view thereof;

FIG. 12 is a left side view thereof;

FIG. 13 is a right side view thereof;

FIG. 14 is a front view thereof;

FIG. 15 is a rear view thereof; and,

FIG. 16 is an environmental perspective view showing the gusset and seat panel of FIG. 9 sewn into a pant garment.

Elements, components and features shown in broken lines form no part of the claimed design. Elements, components and features shown in phantom lines are for illustrative purposes and form no part of the claimed design.

1 Claim, 12 Drawing Sheets
